W. R. DERR,

CLOTHESLINE AND LOCKING CLOTHESPIN THEREFOR.
APPLICATION FILED NOV. 19, 1921.

1,433,344.

Patented Oct. 24, 1922.

UNITED STATES PATENT OFFICE.

WILLIAM R. DERR, OF NEW YORK, N. Y.

CLOTHESLINE AND LOCKING CLOTHESPIN THEREFOR.

Application filed November 19, 1921. Serial No. 516,285.

To all whom it may concern:

Be it known that I, WILLIAM R. DERR, a citizen of the United States, and a resident of the city, county and State of New York, have invented a certain new and useful Improvement in Clothesline and Locking Clothespin Therefor, of which the following is a specification.

This invention relates to clotheslines for supporting clothes so that they may be dried in exposed position in the open air, and particularly to clothes supporting devices provided with means for and which are adapted for locking the clothes upon the clothesline in a secure and positive manner, to thereby prevent unauthorized persons from removing the clothes from the supporting device, as frequently happens when persons other than the owner have access to the house top, lot, yard or other space where the clothes are hung out in the open air to dry.

My invention is particularly adapted for use upon roofs or areaways of apartment houses, as it provides a clothes hanging device wherein and by the use of which each individual occupant is enabled to hang out his clothes after washing, and to lock them securely upon a line while and until they become dry by exposure to the atmosphere.

The object of my invention is to provide an improved clothes supporting and locking device of the type above referred to and in which a plurality of pairs of spring pressed clasping jaws are employed to hold the clothes upon the clothesline, which is entirely separate from the holding and locking elements.

The invention to which this present application relates is an improvement upon the clothes supporting and locking device for which Letters Patent was granted to me upon May 7, 1918, No. 1,265,436. The end in view in making this present invention was to provide a more simple and secure locking device and one which could be manufactured, installed, and kept in proper operation with less attention than in the case of the device to which the patent above referred to relates.

Further objects of my invention as disclosed herein are to provide various improvements in and relating to the locking elements and mechanism whereby the clasping

jaws of locking members are locked closed and to otherwise improve upon and enhance the general efficiency of locking clothes supporting devices of the general class or type to which my invention relates.

My improved clothes supporting and locking device is illustrated in the preferred form in the drawing accompanying and forming a part of this specification; although it will be appreciated the embodiment thereof illustrated may be modified in various ways, and that my invention includes all such variations and modifications of the particular embodiment thereof illustrated and herein described as come within the scope of the concluding claims wherein the features wherein my invention consists are particularly pointed out.

In the drawing accompanying and forming a part of this specification:

Figure 1 is a view showing my improved clothes supporting and locking device installed and in use; Fig. 2 is a side elevation partly broken away and partly in section of my improved clothespin or clasping member; Fig. 3 is a sectional view on the line III—III of Fig. 2; Fig. 4 is a sectional view similar to Fig. 3, but with some of the parts in a different position; Fig. 5 is a sectional view on the line V—V of Fig. 4; Fig. 6 is a sectional view on the line VI—VI of Fig. 3; Fig. 7 is a fragmentary perspective view of a detail of my invention.

Referring now to the drawing, the reference numerals 8 and 9 designate two upright end posts or equivalent supports to which the ends of the clothesline 10 are secured and 11 designate a suitable supporting member extending parallel with and located adjacent the clothesline 10, so that clothes hung upon the line may be locked thereupon by clothespins carried by the supporting member and comprising pairs of cooperating spring closed clasping jaws adapted to engage the clothes as illustrated in Fig. 1.

The clothespins or clasping members are mounted on the support 11 so as to be freely movable longitudinally thereof so that they may be moved to accommodate clothes of different length. The clothespins are designated as a whole by 12 and the construction is shown in Figs. 2 to 6 inclusive.

Each clothespin consists principally of a pair of cooperating clasping jaws 13 and 14

pivotedly connected by pin 15 extending through their overlapping sides and having engaging lower ends 16 which engage the clothes and hold them securely upon the clothesline 10; said jaws being substantially channel shape in cross section and arranged one within the other with their side walls 17 and 18 close together and overlapping one another throughout their entire length; thus providing a hollow box like structure having double side and end walls overlapping one another throughout the greater part of their areas when the pin is closed and locked.

15 In order to support the clothespin upon the support 11 and render it freely movable thereon, each side wall 18 of the pin is formed with an orifice 19 into which the support 11 is inserted and the side walls 17 are formed with a cut away portion 20 so that jaw 13 may be turned on pivot pin 15 in order that clothes may be inserted and withdrawn from the jaws of the pin.

20 In order to lock the pin closed after it embraces one end of the clothes as shown in Fig. 1 a locking bar 21 is provided. This bar is pivotally attached at one end to one end of a bar 22, which bar is pivoted at 23 on post 8; the other end of the locking bar 30 is pivoted to one end of the locking lever 24 pivoted at 25 on post 9. Intermediate the ends of the locking bar are located spacing bars 26, as frequently as desired. These spacing bars are of the same length as bar 22 and are attached pivotally both to 11 and 21. It will be evident that a movement of locking lever 24 on its pivot 25 will cause locking bar 21 to rise and fall vertically.

25 Locking bar 21 is positioned between an upper 27 and a lower 28 extended shoulder of the pin 12. These shoulders are carried by the shoulder slide 29, so that when the locking bar is raised the slide 29 is raised and abuts locking cam 30 by pin 37 pivoted on jaw 14 and moves and holds it in the position shown in Fig. 3 whereby the end bears against the end of the jaw 12 thereby preventing movement of jaw 12 on pivot pin 15 and thereby locking the clothes on the line.

30 In order to unlock jaw 12 the locking bar 21 is lowered by locking lever 24 and shoulder slide 29 is lowered to the position shown in Fig. 4 wherein the locking cam is shown projected into a slot 31 formed in the slide 29. In this position of the locking cam, inward pressure against the upper end of jaw 13 causes the jaw to pivot on pivot pin 15 and the lower end 16 to move away from the corresponding end of jaw 14 so that clothes may be removed.

35 A spring 32 wrapped about pivot pin 15 with one end bearing against cam 30 and the other end against jaw 13 is provided so that the jaws will remain in contact at their

lower ends except when pressure is manually applied at the upper end of the pin to open it.

40 As shown in detail by Fig. 7, a pin 33 is passed through post 9 and the lever 24 when in locking position as shown in Fig. 7, and then if a padlock as 34, Fig. 1, is inserted in hole 35 in pin 33, all of the clothespins will be locked and the clothes engaged thereby be held securely so that only one having a key to the padlock may unlock the pins 75 and remove the clothes.

45 In order to hold the shoulder slide 29 from moving outwardly it is confined by extensions 36, best shown in Fig. 5 of jaw 14.

50 Although I have particularly described the construction of one physical embodiment of my invention, and explained the operation and principle thereof; nevertheless, I desire to have it understood that the form selected is merely illustrative, but does not exhaust 85 the possible physical embodiments of the idea of means underlying my invention.

55 What I claim as new and desire to secure by Letters Patent of the United States, is:

1. In a clothes locking device of the class 90 described, in combination: a suitable support; a plurality of clothespins, each comprising two cooperating clasping jaws, one of which is formed with an orifice through which said support passes, and which jaws 95 are pivotally connected together; a spring acting to close said jaws; a locking cam adapted to lock said jaws closed; a reciprocatable locking bar for operating said cam and means for locking said locking bar. 100

2. In a clothes locking device, in combination: an extended support; two cooperating clasping jaws pivotally connected and movable on said pivot to clasp and unclasp, one of said clasping jaws formed with an orifice 105 through which said support extends for supporting said jaws; a locking cam supported by one of said jaws; means for forcing said cam into engagement with the other jaw so as to lock the jaws closed and means 110 whereby the last named means may be locked.

3. In a clothes locking device, in combination: an extended support; a clothespin, including two cooperating clasping jaws pivotally connected whereby the jaws may be 115 opened and closed and may secure and release objects; and one of the jaws formed with an orifice through which the support extends; a locking cam pivotally connected to the said one of the jaws; an apertured 120 slide bearing against the cam; means for operating the slide whereby the cam is moved into and released from engagement with the other jaw and means whereby the last named means may be locked. 125

4. In a clothes locking device, in combination: an extended support; a plurality of clothespins, each including two cooperating clasping jaws pivotally connected whereby the jaws may be opened and closed and may 130

secure and release objects and one of the jaws formed with an orifice through which the support extends; a locking cam pivotally connected to the said one of the jaws of each of the pins; an apertured slide bearing against the cam of each pin and formed with shoulders; means cooperating simultaneous-

ly with the shoulders of all the pins for operating the slide whereby the cam of each pin is moved into and released from engagement 10 with the other jaw of each pin and means for locking the last named means.

WILLIAM R. DERR.
